(57) **ABSTRACT**

A connector for being arranged at an end of a cable includes a paddle card substrate for electrically connecting the cable to a connected device, plural device-side electrodes that are formed at an end portion of the paddle card substrate in plural rows in an insertion direction into the device and are to be electrically connected to the device, and a protective portion formed between the device-side electrodes adjacent in the insertion direction into the device to protect a surface of the paddle card substrate. The protective portion includes plural metal protective pads that are spaced from each other at a predetermined distance in the insertion direction.

4 Claims, 5 Drawing Sheets

FIG.1**FIG.2*****FIG.3*****FIG.4A****FIG.4B****FIG.5****FIG.6****FIG. 7**## CONNECTOR AND CONNECTOR-EQUIPPED CABLE

The present application is based on Japanese patent application No. 2017-013949 filed on Jan. 30, 2017, the entire contents of which are incorporated herein by reference.

BACKGROUND OF THE INVENTION

1. Field of the Invention

The invention relates to a connector and a connector-equipped cable.

2. Description of the Related Art

Circuit boards provided on so-called IT (Information Technology) devices such as servers or network devices are commonly called "motherboard", and plural connector-equipped cables are connected to the motherboard.

Connector-equipped cable to be used is composed of a cable incorporating plural differential signal transmission cables and connectors provided at both ends of the cable. Each connector incorporates a paddle card substrate for electrically connecting the cable to device such as IT device. Plural device-side electrodes to be electrically connected to the device are formed at an edge of the paddle card substrate.

Along with improved performance of IT devices, it is desired to broaden the transmittable bandwidth of connector-equipped cables. One of the methods to broaden the transmittable bandwidth is to increase the number of channels in a connector-equipped cable. When using this method, it is necessary to increase the number of device-side electrodes on the paddle card substrate. The number of device-side electrodes on the paddle card substrate can be increased when, e.g., device-side electrodes are provided in plural rows as disclosed in JP H10/335019 A.

SUMMARY OF THE INVENTION

FIG. 7 is an explanatory diagram illustrating a prior art disclosed in JP H10/335019 A. FIG. 7 shows an example in which device-side electrodes 40a and 40b are provided on a paddle card substrate 200 so as to form plural rows at one end. The device-side electrodes 40a are provided at a predetermined distance from an end face of the paddle card substrate. The device-side electrodes 40b are provided at a farther distance from the end face of the paddle card substrate than the device-side electrodes 40a. The paddle card substrate 200 is connected to device such as IT device so that the device-side electrodes 40a and 40b are respectively in contact with plural contacts 11a and 11b which are provided inside a connector housing 10 of the device and are electrically connected to a motherboard (not shown). When connecting the paddle card substrate 200 to the device, the paddle card substrate 200 is slid into the connector housing 10 in such a manner that the contacts 11a and 11b slidably move on a surface thereof, and once the contacts 11a and 11b come into contact with the corresponding device-side electrodes 40a and 40b, the connector-equipped cable is completely connected to the device.

However, when the contacts 11a and 11b slidably move on the paddle card substrate 200, a base, which is not covered with the device-side electrodes 40a and 40b and is thus exposed on the surface of the paddle card substrate 200, may be damaged or scraped.

Thus, it is an object of the invention to provide a connector and a connector-equipped cable that can prevent a

base of the paddle card substrate exposed on a surface from being damaged or scraped when the paddle card substrate is connected to device.

According to an embodiment of the invention, a connector for being arranged at an end of a cable comprises:

a paddle card substrate for electrically connecting the cable to a connected device;
a plurality of device-side electrodes that are formed at an end portion of the paddle card substrate in a plurality of rows in an insertion direction into the device and are to be electrically connected to the device; and
a metal protective portion formed between the device-side electrodes adjacent in the insertion direction into the device to protect a surface of the paddle card substrate, wherein the protective portion comprises a plurality of metal protective pads that are spaced from each other at a predetermined distance in the insertion direction.

EFFECTS OF THE INVENTION

According to an embodiment of the invention, a connector and a connector-equipped cable can be provided that can prevent a base of the paddle card substrate exposed on a surface from being damaged or scraped when the paddle card substrate is connected to device.

BRIEF DESCRIPTION OF THE DRAWINGS

FIG. 1 is a plan view showing a connector-equipped cable in the first embodiment of the present invention.

FIG. 2 is a cross sectional view showing a paddle card taken along a line A-A in FIG. 1 and a diagram illustrating a connector housing provided on device.

FIG. 3 is a diagram illustrating one end of a paddle card substrate in Comparative Example 1.

FIG. 4A is a diagram illustrating a simulation result of an effect of crosstalk on the paddle card substrate in the first embodiment.

FIG. 4B is a diagram illustrating a simulation result of an effect of crosstalk on the paddle card substrate in Comparative Example 1.

FIG. 5 is a diagram illustrating a paddle card substrate 5A which constitutes a connector-equipped cable in the second embodiment of the invention.

FIG. 6 is a diagram illustrating a simulation result of an effect of crosstalk on the paddle card substrate in the second embodiment.

FIG. 7 is an explanatory diagram illustrating a prior art.

DETAILED DESCRIPTION OF THE PREFERRED EMBODIMENTS

First Embodiment

The first embodiment of the invention will be described with reference to FIG. 1. FIG. 1 is a plan view showing a connector-equipped cable 1 in the first embodiment of the invention.

As shown in FIG. 1, the connector-equipped cable 1 is provided with a cable 2 having plural differential signal transmission cables 2a, 2b, 2c and 2d, connectors 3 provided at both ends of the cable 2, and paddle card substrates 5 each of which is formed of a multilayer substrate electrically connecting the differential signal transmission cables 2 to device, is incorporated in the connector 3 and is configured that first to fourth device-side electrodes 4a to 4d to be electrically connected a connected device (not shown) are

formed at one end **51** of a base **53** and the differential signal transmission cables **2** are connected to another end **52**.

In the first embodiment, the connector-equipped cable **1** configured to be able to transmit and receive on two channels will be described. In this case, four differential signal transmission cables **2a**, **2b**, **2c** and **2d** in total, two for transmission and two for reception, are provided. The connector-equipped cable **1** is used for, e.g., transmitting and receiving signals of 25 Gbps.

Cable-connecting electrodes **6a** electrically connected to the differential signal transmission cable **2a**, cable-connecting electrodes **6b** electrically connected to the differential signal transmission cable **2b**, cable-connecting electrodes **6c** electrically connected to the differential signal transmission cable **2c** and cable-connecting electrodes **6d** electrically connected to the differential signal transmission cable **2d** are formed at the other end **52** (an end on a side on which the cable **2** is connected) of the paddle card substrate **5** (the base **53**).

Coupling capacitors **7a** are connected, via an inner layer of the multilayer substrate, to the cable-connecting electrodes **6a** on a side opposite to the side on which the differential signal transmission cable **2a** is connected. Coupling capacitors **7b** are connected to the cable-connecting electrodes **6b** on a side opposite to the side on which the differential signal transmission cable **2b** is connected. Coupling capacitors **7c** are connected, via the inner layer of the multilayer substrate, to the cable-connecting electrodes **6c** on a side opposite to the side on which the differential signal transmission cable **2c** is connected. Coupling capacitors **7d** are connected to the cable-connecting electrodes **6d** on a side opposite to the side on which the differential signal transmission cable **2d** is connected.

Each coupling capacitor **7a** is arranged so that a terminal opposite to the terminal connected to the cable-connecting electrode **6a** is connected to the first device-side electrode **4a** via the inner layer of the multilayer substrate. Each coupling capacitor **7b** is arranged so that a terminal opposite to the terminal connected to the cable-connecting electrode **6b** is connected to the second device-side electrode **4b** via the inner layer of the multilayer substrate. Each coupling capacitor **7c** is arranged so that a terminal opposite to the terminal connected to the cable-connecting electrode **6c** is connected to the third device-side electrode **4c** via the inner layer of the multilayer substrate. Each coupling capacitor **7d** is arranged so that a terminal opposite to the terminal connected to the cable-connecting electrode **6d** is connected to the fourth device-side electrode **4d** via the inner layer of the multilayer substrate.

In other words, the first device-side electrodes **4a** are connected to the differential signal transmission cable **2a** via the coupling capacitors **7a** and the cable-connecting electrodes **6a**. The second device-side electrodes **4b** are connected to the differential signal transmission cable **2b** via the coupling capacitors **7b** and the cable-connecting electrodes **6b**. The third device-side electrodes **4c** are connected to the differential signal transmission cable **2c** via the coupling capacitors **7c** and the cable-connecting electrodes **6c**. The fourth device-side electrodes **4d** are connected to the differential signal transmission cable **2d** via the coupling capacitors **7d** and the cable-connecting electrodes **6d**.

The device-side electrodes **4a**, **4b**, **4c** and **4d** are formed at the one end **51** of the paddle card substrate **5** and are lined up in plural rows in an insertion direction into device. The first device-side electrodes **4a** and the third device-side electrodes **4c** are formed at positions located at a predetermined distance **D1** away from an end face **51a** of the one end

51 of the paddle card substrate in the insertion direction into the device and are aligned in a row parallel to the end face **51a**. The second device-side electrodes **4b** and the fourth device-side electrodes **4d** are formed at positions located at a predetermined distance **D2** away from the end face **51a** of the one end of the paddle card substrate in the insertion direction into the device and are aligned in a row parallel to the end face **51a**. **D2** is greater than **D1**, so the second device-side electrodes **4b** and the fourth device-side electrodes **4d** are located at a farther distance from the end face **51a** of the one end **51** of the paddle card substrate in the insertion direction into the device than the first device-side electrodes **4a** and the third device-side electrodes **4c**. In other words, the first device-side electrodes **4a** and the third device-side electrodes **4c** form an electrode group in the first row, and the second device-side electrodes **4b** and the fourth device-side electrodes **4d** form an electrode group in the second row.

20 Facing end faces of the first device-side electrodes **4a** and the second device-side electrodes **4b** are spaced apart by, e.g., a distance **D3** of not less than 2.0 mm. Likewise, facing end faces of the third device-side electrodes **4c** and the fourth device-side electrodes **4d** are spaced apart by, e.g., the distance **D3** of not less than 2.0 mm.

25 A ground pattern, a power electrode (not shown) and a control signal electrode (not shown), etc., as well as the device-side electrodes **4a**, **4b**, **4c** and **4d**, are formed and aligned on a surface of the paddle card substrate **5** at the one end **51**, and a card edge connector is thereby formed.

30 The ground pattern is composed of a first ground pattern **81** formed to sandwich the first device-side electrodes **4a** and the third device-side electrodes **4c**, a second ground pattern **82** formed to sandwich the second device-side electrodes **4b** and the fourth device-side electrodes **4d**, a third ground pattern **83** formed between the first ground pattern **81** and the second ground pattern **82**, a fourth ground pattern **84** formed to sandwich the cable-connecting electrodes **6a**, **6b** and **6c**, and a fifth ground pattern **85** formed on transmission paths between the first to fourth device-side electrodes **4a** to **4d** and the cable-connecting electrodes **6a**, **6b**, **6c** and **6d**.

35 The second ground pattern **82**, the fourth ground pattern **84** and the fifth ground pattern **85** are continuous and form an integral pattern. The first ground pattern **81** and the third ground pattern **83** are not connected to the other patterns and do not form the integral pattern.

40 First protective portions **91** made of a metal are formed on the surface of the paddle card substrate **5** between the first device-side electrodes **4a** and the second device-side electrodes **4b**. Second protective portion **92** made of a metal are also formed on the surface of the paddle card substrate **5** between the third device-side electrodes **4c** and the fourth device-side electrodes **4d**. Each first protective portion **91** is composed of two protective pads **91a** and **91b** which are spaced at a predetermined distance in the insertion direction of the paddle card substrate into the device. Each second protective portion **92** is composed of two protective pads **92a** and **92b** which are spaced at a predetermined distance in the insertion direction of the paddle card substrate into the device. The protective pads **91a** and **91b** are spaced from each other at a distance **D4** of not less than 0.05 mm and not more than 0.25 mm, and so are the protective pads **92a** and **92b**. When **D4** is less than 0.5 mm, it is difficult to form the protective pads **91a**, **91b**, **92a** and **92b** in manufacturing. When **D4** is more than 0.25 mm, the distances between the protective pads **91a** and **91b** and between the protective pads

92a and 92b are too large and a function of protecting the surface of the paddle card substrate 5 is not sufficient.

Third protective portions 93 made of a metal are formed between the end face 51a of the paddle card substrate 5 and the first device-side electrodes 4a. Fourth protective portions 94 made of a metal are formed between the end face 51a of the paddle card substrate 5 and the third device-side electrodes 4c.

The first protective portions 91, the second protective portions 92, the third protective portions 93 and the fourth protective portions 94 are not electrically connected to any device-side electrodes or ground patterns, and thus are electrically floating from other electrodes.

The first protective portions 91, the second protective portions 92, the third protective portions 93 and the fourth protective portions 94 are formed of the same material as the first device-side electrodes 4a, the second device-side electrodes 4b, the third device-side electrodes 4c and the fourth device-side electrodes 4d. Use of the same material allows the first protective portions 91, the second protective portions 92, the third protective portions 93 and the fourth protective portions 94 to be simultaneously formed in the process of forming the device-side electrodes 4a, 4b, 4c and 4d on the base 53 of the paddle card substrate 5.

Next, movement when inserting the connector-equipped cable 1 into a connector housing 10 provided on device will be described with reference to FIG. 2. FIG. 2 shows the paddle card 5 in a cross sectional taken along the line A-A in FIG. 1 and the connector housing 10 provided on device. In FIG. 2, the fifth ground pattern and the cable 2, etc., are omitted.

When connecting the connector-equipped cable 1 to device, the connector-equipped cable 1 is inserted into the connector housing 10 by sliding to bring the first device-side electrodes 4a into contact with first contacts 11a provided on the inner side of the connector housing 10 and to bring the second device-side electrodes 4b into contact with second contacts 11b provided on the near side of the connector housing 10. The first device-side electrodes 4a and the second device-side electrodes 4b are respectively brought into contact with and electrically connected to the first contacts 11a and the second contacts 11b.

The first contacts 11a slidably move on the third protective portions 93 in the course of sliding on the paddle card substrate 5 to the positions where the first contacts 11a come into contact with the first device-side electrodes 4a. The second contacts 11b slidably move on the protective portions 93, the first device-side electrodes 4a and the protective pads 91a and 91b of the first protective portions 91 in the course of sliding on the paddle card substrate 5 to the positions where the second contacts 11b come into contact with the second device-side electrodes 4b. Since the protective portions 93 and the protective pads 91a and 91b are provided on the paddle card substrate 5, the first contacts 11a and the second contacts 11b are prevented from slidably moving on the base 53 exposed on the surface and thus do not damage or scrape the surface. Likewise, since the fourth protective portions 94 and the second protective portions 92 are provided on the paddle card substrate 5, other contacts (not shown) inside the connector housing 10 are prevented from slidably moving on the base 53 exposed on the surface and thus do not damage or scrape the surface, even though the explanation thereof is omitted.

Next, the first protective portion 91 and the second protective portion 92 will be further described using Comparative Example 1. FIG. 3 is a diagram illustrating one end of a paddle card substrate 500 in Comparative Example 1.

Unlike the paddle card substrate 5 in the first embodiment, the paddle card substrate 500 in Comparative Example 1 is configured that each of first protective portions 910 and second protective portions 920 is formed of one protective pad. The remaining configuration of Comparative Example 1 is the same as the first embodiment.

An effect of a signal applied to each of the device-side electrodes 4a, 4b, 4c and 4d on the other device-side electrodes 4a, 4b, 4c and 4d adjacent thereto was examined on the paddle card substrate 5 of the first embodiment and the paddle card substrate 500 of Comparative Example 1. In detail, a signal appearing at the first device-side electrode 4a when applying a signal to the second device-side electrode 4b was simulated using electromagnetic analysis. In other words, an effect of crosstalk on the first device-side electrode 4a when applying a signal to the second device-side electrode 4b was simulated. The simulation results are shown in FIGS. 4A and 4B. FIG. 4A shows a simulation result of an effect of crosstalk on the paddle card substrate 5 in the first embodiment and FIG. 4B shows a simulation result of an effect of crosstalk on the paddle card substrate 500 in Comparative Example 1.

As shown in the simulation results of FIGS. 4A and 4B, crosstalk peaks appear at bandwidths of around 20 GHz and around 40 GHz in the paddle card substrate 500 of Comparative Example 1. In the paddle card substrate 5 of the first embodiment, the crosstalk peaks are smaller than those in Comparative Example 1 and the value of integrated crosstalk relative to frequency is small. This shows that the effect of crosstalk is smaller in the first embodiment than in Comparative Example 1. In other words, the effect of crosstalk in the connector-equipped cable 1 of the first embodiment is reduced by forming the first protective portion 91 (the second protective portion 92) using two (plural) members.

A resin member may be provided in a gap between the protective pads 91a and 91b of the first protective portion 91. The resin member preferably has a higher abrasion resistance and a lower coefficient of friction than the base 53 of the paddle card substrate 5. The base 53 of the paddle card substrate 5 is formed of, e.g., FR4 (Flame Retardant 4). The resin member is formed of, e.g., Teflon (registered trademark) resin. By having the resin member in a gap between the protective pads 91a and 91b, the paddle card substrate 5 can prevent the first contacts 11a and the second contacts 11b from slidably moving on the base 53 exposed on the surface. A resin member may be also provided in a gap between the protective pads 92a and 92b of the second protective portion 92 in the same manner.

The first ground pattern 81, the second ground pattern 82 and the third ground pattern 83 may be formed as one continuous pattern.

Effects of the First Embodiment

The connector 3 and the connector-equipped cable 1 in the first embodiment are configured that the first and second protective portions 91 and 92 made of a metal are formed on the surface of the paddle card substrate 5 between the first device-side electrodes 4a and the second device-side electrodes 4b and between the third device-side electrodes 4c and the fourth device-side electrodes 4d. This prevents damage or scrape on the base 53 exposed on the surface of the paddle card substrate 5 when connecting the paddle card substrate 5 to device.

In addition, since the first protective portion 91 (the second protective portion 92) is formed of plural metal protective pads 91a and 91b (92a and 92b) which are spaced at a predetermined distance in the insertion direction of the

paddle card substrate 5 into the device, it is possible to reduce the effect of crosstalk between adjacent device-side electrodes as compared to when each of the first protective portion 91 and the second protective portion 92 is formed of one protective pad.

Second Embodiment

Next, the second embodiment of the invention will be described with reference to FIG. 5. The difference between the connector-equipped cable 1 in the first embodiment and a connector-equipped cable in the second embodiment is in a configuration at one end of the paddle card substrate. Therefore, the configuration of one end of a paddle card substrate 5A in the second embodiment will be described below. FIG. 5 is a diagram illustrating the paddle card substrate 5A which constitutes a connector-equipped cable in the second embodiment of the invention. The same constituent elements as those of the paddle card substrate 5 in the first embodiment are denoted by the same reference numerals, and the explanation thereof will be omitted.

The paddle card substrate 5A in the second embodiment is configured that a non-metallic first protective portion 91A is formed between the first device-side electrodes 4a and the second device-side electrodes 4b in place of metal protective portions. Likewise, the paddle card substrate 5A is configured that a non-metallic second protective portion 92A is formed between the third device-side electrodes 4c and the fourth device-side electrodes 4d in place of metal protective portions. The first protective portion 91A and the second protective portion 92A are formed of, e.g., resin or ceramic, etc. The first protective portion 91A and the second protective portion 92A are preferably formed of a material which has a higher abrasion resistance and a lower coefficient of friction than the base 53 of the paddle card substrate 5A.

An effect of a signal applied to each of the device-side electrodes 4a, 4b, 4c and 4d on the other device-side electrodes 4a, 4b, 4c and 4d adjacent thereto was examined on the paddle card substrate 5A of the second embodiment in the same manner as the first embodiment. In detail, a signal appearing at the first device-side electrode 4a when applying a signal to the second device-side electrode 4b was simulated using electromagnetic analysis. In other words, an effect of crosstalk on the first device-side electrode 4a when applying a signal to the second device-side electrode 4b was simulated. The simulation result is shown in FIG. 6.

As shown in the simulation results of FIGS. 6 and 4B, crosstalk peaks appear at bandwidths of around 20 GHz and around 40 GHz in the paddle card substrate 500 of Comparative Example 1. In the paddle card substrate 5A of the second embodiment, the crosstalk peaks are smaller than those in Comparative Example 1 and the value of integrated crosstalk relative to frequency is small. This shows that the effect of crosstalk is smaller in the second embodiment than in Comparative Example 1. In other words, the effect of crosstalk in the connector-equipped cable of the second embodiment is reduced by forming the first protective portion 91 (the second protective portion 92) using a non-metallic member.

Effects of the Second Embodiment

The connector and the connector-equipped cable in the second embodiment are configured that the non-metallic first and second protective portions 91A and 92A are formed on the surface of the paddle card substrate 5A between the first device-side electrodes 4a and the second device-side electrodes 4b and between the third device-side electrodes 4c and the fourth device-side electrodes 4d. This prevents

damage or scrape on the base 53 exposed on the surface of the paddle card substrate 5 when connecting the paddle card substrate 5A to device.

In addition, since the first protective portion 91A and the second protective portion 92A are formed of non-metallic members, it is possible to reduce the effect of crosstalk between adjacent device-side electrodes.

Although the embodiments of the invention have been described, the invention according to claims is not to be limited to the embodiments. Further, please note that all combinations of the features described in the embodiments are not necessary to solve the problem of the invention.

For example, although an example in which device-side electrodes and protective portions, etc., are formed on one surface of the paddle card substrate 5 or 5A has been described in the first and second embodiments, the device-side electrodes and the protective portions, etc., may be formed also on the other surface in the same manner.

REFERENCE SIGNS LIST

- 1 . . . Connector-Equipped Cable
- 2 . . . Cable
- 3 . . . Connector
- 4a . . . First Device-Side Electrode
- 4b . . . Second Device-Side Electrode
- 4c . . . Third Device-Side Electrode
- 4d . . . Fourth Device-Side Electrode
- 5, 5A . . . Paddle Card Substrate
- 91 . . . First Protective Portion
- 92 . . . Second Protective Portion

What is claimed is:

1. A connector for being arranged at an end of a cable, the connector comprising:
a paddle card substrate for electrically connecting the cable to a connected device;
a plurality of device-side electrodes that are formed at an end portion of the paddle card substrate in a plurality of rows in an insertion direction into the device and are to be electrically connected to the device; and
a protective portion formed between the device-side electrodes adjacent in the insertion direction into the device to protect a surface of the paddle card substrate;
wherein the protective portion comprises a plurality of metal protective pads that are spaced from each other at a predetermined distance in the insertion direction;
wherein the protective portion comprises the two protective pads that are spaced from each other at a distance of not less than 0.05 mm and not more than 0.25 mm in the insertion direction.
2. The connector according to claim 1, wherein the protective portion further comprises a resin member provided between the plurality of spaced protective pads.
3. A connector-equipped cable, comprising:
a cable; and
a connector provided at an end of the cable,
wherein the connector comprises a paddle card substrate for electrically connecting the cable to a connected device, a plurality of device-side electrodes that are formed at an end portion of the paddle card substrate in a plurality of rows in an insertion direction into the device and are to be electrically connected to the device, and a metal protective portion formed between the device-side electrodes adjacent in the insertion direction into the device to protect a surface of the paddle card substrate, and

wherein the protective portion comprises a plurality of protective pads that are spaced from each other at a predetermined distance in the insertion direction; wherein the protective portion has a higher abrasion resistance and a lower coefficient of friction than a base 5 of the paddle card substrate.

4. A connector for being arranged at an end of a cable, the connector comprising:

a paddle card substrate for electrically connecting the cable to a connected device; 10 a plurality of device-side electrodes that are formed at an end portion of the paddle card substrate in a plurality of rows in an insertion direction into the device and are to be electrically connected to the device; and a non-metallic protective portion formed between the 15 device-side electrodes adjacent in the insertion direction into the device to protect a surface of the paddle card substrate; wherein the protective portion has a higher abrasion resistance and a lower coefficient of friction than a base 20 of the paddle card substrate.
